SHIFTABLE SUPPORT FOR IRONERS

Leo M. Kahn, Brooklyn, N. Y.

Application April 30, 1946, Serial No. 666,119

4 Claims. (Cl. 38—60)

1

This invention relates to ironing or pressing machines and more particularly to a power-driven ironing machine of the roll type or modifications thereof.

Such machines generally comprise a heated ironing shoe adapted to iron or press the fabric against a rotatable roll. The ironing of flat fabrics or garments imposes no particular problem but curved articles such as shirt collars, sleeves, dresses, ruffled curtains, etc. offer considerable difficulties if it is attempted to iron them in the ordinary manner. It is apparent that such ironing would produce creases in curved articles. In order to overcome this difficulty, the art generally practices the end application of fabrics in respect to the roll. Thus, a sleeve or other curved article may be applied endwise of the roll which may thereupon fit inside the curved article so as to permit it to be ironed without creases, or the curved portions of articles such as collars and cuffs may be placed between the roll and heated shoe while the balance of the article is free thereof. Since the operator is generally seated in front of the machine, it is apparent that she must move in her seat and lean toward the free end of the roll in order to perform the above operation. The roll is usually sufficiently elongated for wide articles so that the operator is required to move to a substantial extent in order to reach the open end of the roll. This is manifestly both a time and energy consuming operation. It should be observed that machines of this type may be used in commercial laundries wherein many articles are continuously ironed by one operator. The burden imposed by the requirement of moving toward the end of the machine each time that a curved article or a curved part of the substantially flat article must be ironed, is considerable.

Bearing the foregoing in mind, it is an object of the present invention to provide a rotating ironing or pressing machine which will make possible the treatment of curved articles without requiring the operator to deviate from a fixed position which is adaptable for all kinds of operations. The saving in time and energy effected thereby, results in less fatigue for the operator while increasing her production, factors which are generally highly regarded and sought after in the industry.

Other objects of my invention will be apparent from the following description, it being understood that the above general statements of the objects of my invention are intended to describe and not limit it in any manner.

2

Referring to the drawings:

Fig. 1 is an end view, partly broken away, of an ironing machine constructed according to the instant invention.

5 Fig. 2 is a top view thereof illustrating the apparatus in rotating position for presenting the end thereof to the operator.

Fig. 3 is a front view of the machine in the normal position.

10 Fig. 4 is a section along the line 4—4 of Fig. 3.

Fig. 5 is an end view illustrating the normal position of the operator as viewed along the line 5—5 of Fig. 4.

15 Fig. 6 is a modification illustrating an adaptation of the invention to a portable type of such ironing machines.

Figs. 7, 7A and 7B are top views illustrating a modified embodiment of the invention and the positions of the ironing roll in adapting the machine to end operation.

20 Figs. 8, 8A and 8B are top views of another modified embodiment of the invention and illustrate the positions of the ironing roll in adapting the machine to end operation.

25 Figs. 9 and 9A are top views of still another embodiment of the invention and illustrate the positions of the ironing roll in adapting the machine to end operation.

Referring to Figs. 1 to 5, the machine is illustrated as being supported on a table 15 having legs 16 which may have an offset portion 17 in order to provide the table with a degree of stability. Supported by the table 15 is a machine base 18 upon which is mounted the roll 19 and shoe 20 as well as the gooseneck element 21.

30 The usual gooseneck casing element 21 is secured in any suitable manner to the base 18, such gooseneck casing element 21 serving to house, in whole or in part, an electrical motor 22 and conventional transmission means therefrom so as to effect and control the rotation of roll 19. The disposition and construction of the motor and transmission means are well known to those skilled in the art and need not be described herein.

35 The actuation of shoe 20 is controlled by shoe operating arm 23 disposed in slot 24 formed in both the base 18 and table 15 when the roll is in the normal position. The lower end of shoe operating arm 23 is received in a slot of member 25 so as to be securely connected thereto. A hollow control arm 26 is secured to pivotally mounted member 25 so that the movements of

40 said control arm 26 are transmitted through member 25 to the shoe operating arm 23. Mem-

ber 25 serves to receive the electrical lead wires 27 as they travel from a slot formed in base 18 into the hollow of control arm 26. Member 25 is a short steel rod which is pivotally mounted, as by the pivot point 31, across the slots 24. Member 25 is itself slotted to receive and engage the arm 23 and it is likewise connected to control arm 26 so that it serves to transmit the motion thereof to the arm 23 and shoe 20.

A handhold member 28 is connected to the control arm 26 so as to permit manual guidance thereof. A switch device 29 having the usual pair of electrical contacts is arranged to be actuated by the rotation of handhold member 28 as indicated by the arrow of Fig. 3. Rotation, therefore, of member 28 may serve to close the electrical circuit of motor 22, applying electricity thereto from the plug 30 and effecting the rotation of roll 19. Conventional methods may be utilized for heating the shoe 20 as by electric wires in the operating arm 23. The actuating structure for the shoe 20 is not shown in detail, the operation thereof being well understood. Briefly, when the handhold member 28 is pushed away from the operator, as indicated in Fig. 1, the shoe operating arm 23 is pivoted forward from the pivot point 31 in the manner of a lever. The shoe 20 is thereupon brought inwardly so as to press against the roller 19. Conversely, when the handhold member 28 is pulled toward the operator, the shoe 20 is released.

The present invention provides means for reorienting the roll and shoe structure so as to cause the free end thereof to face the operator as the operator remains seated on the stool 32 disposed at the front of the machine. Accordingly, the machine including its base 18 is arranged to pivot or swing on the table 15 so as to turn 90 degrees in respect thereto. Simultaneously, means are provided to bring the end of roll 19 into a position substantially flush with the operator's side of table 15 so that it assumes substantially the same vertical position as normally occupied by the side of the roll and therefore does not jut out and disturb the operator or cause her to move backward. Thus, a pivot rod 35 is secured in the table 15 so as to permit the base 18 to rotate in respect thereto. Pivot rod 35 is disposed through a suitable bore in table 15 and its upper portion 36 is received in a recess of base 18. The upper portion 36 thereof may be threaded, if desired, so as to mate with a complementary threaded cavity in base 18. In order to provide stability for the ironing machine during its rotating travel and in either of its positions, an arm 37 which may be integral with the pivot rod 35 extends along the underside of table 15 and bears thereagainst so as to provide support for the ironing machine. A ball 38 rotatably maintained in a recess 39 of arm 37, acts as an antifriction member and describes an arcuate path on the underside of table 15 as the machine is rotated. If desired, a groove may be formed in said underside so as to define the arcuate path of the ball 38 and guide the movement of the machine.

Referring to Fig. 4, an arcuate slot 40 may be formed in the table 15 so as to permit the motor 22 to swing along with the ironing machine to the end operating position. Such slot 40 is only necessary when the motor 22 is under or has a portion thereof extending through the table 15. If the motor 22, however, is confined to the gooseneck casing element 21, the slot 40 will be unnecessary.

The operation of the machine will be understood from the above description. If the operator desires to actuate the roller 19, she will rotate handhold member 28 so as to close the electrical circuit of motor 22. The operator may then pull or push the member 28 depending upon whether the shoe 20 is to be engaged with the roll 19 or released therefrom. These specific details form no part of the present invention and are conventional and well known in the art in many forms. When an article having a degree of curvature therein is to be ironed, the operator need merely swing the machine on its pivot 35 as by grasping the left-hand side of base 18 and pulling it toward her. Similarly, she may push against the gooseneck casing element 21 so as to swing it rearwardly. Thus, from a first position where the respective longitudinal axes of the roll 19 and support 15, are parallel, the machine will assume a second position illustrated in Fig. 2 and its end will face the operator's side of support 15 and will be flush with the edge thereof as illustrated in Fig. 5. The base 18 is thus swung in a horizontal plane over an arc of substantially 90 degrees in order to present the free end of roll 19 toward the operator's seat whereas formerly a side portion of the roll 19 was thus presented and the roll is rearwardly moved in order that its free end occupies substantially the same vertical plane as occupied by that side of the roll which faced the operator before the roll was swung. In other words, if both positions could be assumed at the same time, the end of the roll would be superimposed over the side of the roll, indicating that the operator need not move from her standing or sitting position when the roll is swung. In this position of the roll it may be said that its longitudinal axis bisects the longitudinal axis of the support. The machine which is superimposed in the normal position over the support 15 so as to be substantially co-extensive therewith is swung to a position wherein its longitudinal axis is perpendicular to that of the support in its normal position. It will be observed that by disposing the pivot rod 35 a distance from the left end of the table 15 along its further side edge which approximates the width of the table 15 upon which the base 18 rests, the front end of the base 18 is brought substantially flush with the operator's side of support or table 15. The free end of roll 19 is thereby made conveniently available to the operator for the insertion of curved articles thereon.

In Fig. 6 is illustrated the application of the above principles to a portable type of ironing machine resting on an ordinary table T. The ironing machine has its roll 19, shoe 20, gooseneck casing 21 and base 45 on its own support 49. Upon base or goose-neck support 45 is mounted the hand control member 46. A pivot rod 47 is secured to the support 49 and is received into a complementary member in base 45 so as to provide a pivot point for the portable ironing machine. The improved construction is thus made adaptable to this well known type of machine and is considered an important aspect of the invention. The machine may be removed as desired from the table T which need not form part of the structure but may be any type of support. Pivot rod 47 is preferably, but not necessarily, so disposed in relation to the support 49 and base or goose-neck support 45 that the end 48, which may be referred to as the free end of roll 19, may be swung so that it is sub-

stantially flush with the operator's side of support 49. The ironing operations are conducted as in the previous embodiment it being only necessary to push against the power drive casing 21 in order to swing the apparatus from a normal ironing position where a side portion of the roll is accessible to an operator, to a position where the free end of the roll is thus accessible.

In Figs. 7, 7A and 7B is illustrated a modified embodiment wherein the ironing machine may be swung with a pivot pin traveling in a slot disposed substantially centrally of the support. The support 50 is formed with a pivot receiving slot 51, the pivot point or rod 52 swingably connecting the base or goose-neck support 53 to the support 50. In order to simplify the construction of slot 51, the handhold member 54 is mechanically connected to the shoe operating arm 55 through the power drive casing 56 which houses the motor for the roll 57 as in the first embodiment. Such mechanical construction wherein the shoe operating arm 55 is actuated by the handhold member 54 through the casing 56 is conventional, the arm 55 being disposed above the base 53 together with the casing 56.

The handhold member 54 similarly serves as an electrical switching means and is connected to the arm 58 which enters the casing 56. The end 59 of arm 58 is arranged to travel in an arcuate slot 60 so as to permit the arm 58 and casing 56 to travel together towards the rear side edge of support 50.

When the support 53 is swung in the direction of the arc of Fig. 7, the ironing machine first assumes the position illustrated in Fig. 7A where the free end of roll 57 faces the operator's position. The pivot rod 52 has rotated but has not moved along the slot 51. At this point, the operator pushes the base 53 away from her as indicated by the arrow of Fig. 7A so that the rod 52 travels toward the other end of the slot 51 as illustrated in Fig. 7B. It will be apparent, therefore, that the free end of the roll 57 is rendered conveniently accessible to the operator without requiring her to move in her seat.

In Figs. 8, 8A and 8B, an alternative method of accomplishing the objective is illustrated which does not bring the base toward the operator during the swinging thereof to any appreciable extent. Utilizing the method of shoe operation of the first embodiment, the handhold member 62 is arranged to actuate the shoe operating arm 63 through the arm 64. A pivot pin 65 which, as in the previous embodiment, is secured to the underside of the base 66, is arranged to rotate and travel in slot 67 formed in the support 68. The ironing machine is made to present its free end to the operator by first pushing the base 66 in the direction of the arrow shown in Fig. 8 so that the machine assumes the position illustrated in Fig. 8A. The base 66 may then be pivoted about the pivot pin 65 as indicated by the arrow of Fig. 8A so as to bring the free end of the machine towards the operator, as illustrated in Fig. 8B. In order to accommodate the travel of shoe arm 63, a substantially D-shaped slot 69 is formed in the table 68.

Referring to Figs. 9 and 9A, a method of accomplishing the objective of the previous two embodiments with a single swinging movement is illustrated. Thus, the support 70 is formed with a cutout 71 which accommodates the travel of a shoe operating arm disposed in slot 72 of 75

base 73. Support 70 is formed with an arcuate slot 74 in which the pivot pin 75 rides. In order to bring the free end of the machine adjacent to the operator's sitting position, the base 73 is swung in the direction of the arrow of Fig. 9 whereupon the pivot pin 75 simultaneously rotates and travels rearwardly as guided by slot 74 so that the machine assumes the position illustrated in Fig. 9A. In order to lend a degree of stability or security to the rotatable base 73, a bracing plate 76 is secured thereto in the same manner as the arm 37 of the embodiment shown in Figs. 1 to 5. Two anti-friction rollers 77 bear against the underside of support 70 to provide such stability.

I have shown a preferred embodiment of my invention, but it is obvious that numerous changes and omissions may be made therefrom without departing from its spirit.

I claim:

1. In an ironing machine having a shoe, an elongated roll and a motor operatively connected to one end of said roll, the other end of the roll being free, an elongated support for said machine, a pivot pin connected to said machine at a point spaced horizontally from said motor, said support being formed with an elongated slot therein in which said pivot pin rides, said pivot pin being operative to maintain said roll and support in a first position where they are in a superimposed relationship with their respective longitudinal axes parallel, said pivot pin being further operative to permit said roll together with its shoe and motor to revolve in a horizontal plane until said axis of said roll is perpendicular to and bisects the longitudinal sides of said support whereby a second position is assumed where the unconnected or free end of said roll faces in a direction which is faced by a side of said roll when in said first position, said slot formed in said support being effective in permitting said pivot pin and machine to be moved rearwardly relative to said support until the unconnected end of said roll is substantially flush with and disposed centrally of a side or working edge of said support.

2. In an ironing machine having a shoe, an elongated roll and a motor connected to one end of said roll, the other end being free, an elongated support for said machine, said support having one side thereof adapted to face an operator of the machine, a pivot pin spaced horizontally from said motor and connected to said machine, said support being formed with an arcuate slot therein in which said pivot pin rides, said pivot pin being operative to maintain said roll and support in a first position where they are in a superimposed relationship with their respective longitudinal axes parallel, said pivot pin being further operative to permit said roll together with its shoe and motor to revolve in a horizontal plane while simultaneously moving rearwardly in relation to said operator's side of said support until said axis of said roll is perpendicular to and bisects the longitudinal sides of said support whereby a second position is assumed where the unconnected or free end of said roll faces the operator's side of said support, said arcuate slot formed in said support being effective in permitting simultaneous and lengthwise and rearward movement in relation to said operator's side of said support until the free end of said roll is substantially flush with and centrally of the side or working edge of said support while substan-

tially maintaining said roll against forward movement past the edge of said operator's side of said support during said simultaneous movement.

3. In an ironing machine having a shoe, an elongated roll and power drive means connected to one end thereof, the other end being free, a mounting base for said machine, a support for said machine, said mounting base and support being substantially rectangular and having a normal relationship wherein their respective longitudinal axes are parallel and wherein the length of said roll extends along and is substantially flush with the side or working edge of said support, and pivot means connected to said base and spaced horizontally inwardly from said power drive means and connecting said support to said base so that said support pivots at an inward point thereof relative to said power drive means, said support having a slot formed therein in which said pivot means rides, said pivot means being operative to permit said base together with said roll to move in a horizontal plane relative to said support until said longitudinal axes are perpendicular, said pivot means permitting such a degree of rearward movement of said base in conjunction with said movement in a horizontal plane whereby the other or free end of said roll is brought substantially flush with and centrally of said side or working edge of said support.

4. In an ironing machine having a shoe, an elongated roll and power drive means connected to one end thereof, the other end being free, a mounting base for said machine, a support for said machine, said mounting base and support being substantially rectangular and having a normal relationship wherein their respective lon-

10
15

gitudinal axes are parallel and wherein the length of said roll extends along and is substantially flush with the side or working edge of said support, and pivot means spaced horizontally inwardly from said power drive means and connecting said support to said base so that said support pivots at an inward point thereof relative to said power drive means, said pivot means being operative to permit said base together with said roll to move in a horizontal plane relative to said support until said longitudinal axes are perpendicular, said pivot means permitting such a degree of rearward movement of said base in conjunction with said movement in a horizontal plane whereby the other or free end of said roll is brought substantially flush with and centrally of said side or working edge of said support, and a bracing arm connected to said base and acting against the underside of said support to stabilize said base in relation to said support during said movement in a horizontal plane and in the position of said base achieved thereby.
